DEVICE FOR TESTING SPARK PLUGS AND
IGNITION CIRCUITS

James Tawyer, Lisarow, Australia

Application November 13, 1936, Serial No. 110,742
In Australia November 22, 1935

4 Claims. (Cl. 175—183)

This invention relates to devices for testing spark plugs and ignition circuits.

Heretofore in the devices commonly used for testing spark plugs and ignition circuits, it has been necessary to hold the device in position against a spark plug while testing, and this has been awkward, particularly when the driver is alone and it is desired to turn the engine over while each plug is separately tested.

10 Now the present invention has been specially devised to obviate the above mentioned disabilities, and to provide a handy device of compact and sturdy form which is attachable to a spark plug or other suitable point and remains firmly in place while tests are carried out.

This improved device for testing spark plugs and ignition circuits consists of a pair of jaw members shaped at one end to engage with a spark plug terminal or the like, and fulcrumed 20 or pivoted together at a suitable point and having spring means embodied normally to close the shaped jaw ends to cause them to grip a surface. Suitable handles of insulating material are moulded upon, or otherwise affixed to the jaw 25 members, and an electrode or adjustment rod is pivotally mounted in relation to the said jaw members and electrically insulated therefrom and is adapted to be adjusted relatively to the metal body of a spark plug or other suitable part 30 for testing purposes.

This adjustment rod is preferably pivoted between the jaw members and has a finger grip at its outer end of insulating material and may be adjusted out from the said jaw members by sliding through a mounting element or by screwing through a nut or by other means. A spark gap is preferably embodied at its outer end.

The handles are preferably shaped to prevent the fingers of an operator slipping off and touching the metal parts of the jaw members.

In order more fully to describe this invention reference will be made to the drawing accompanying and forming part of this complete specification and wherein:

45 Fig. 1 shows a plan of one construction of the improved device for testing spark plugs and ignition circuits, while

Fig. 2 is another view partially in section on line 2—2 in Fig. 1, and

50 Fig. 3 is an enlarged sectional view of the adjustment rod showing the spark gap end.

The jaw members 4 have outer ends curved at 5 to engage a surface such as the terminal end of a spark plug 7 (indicated in dotted lines in Fig. 2) or other suitable point, and such curved

ends 5 are out-turned at the extremities 6 and reduced in depth as shown in Fig. 2. Handles 8 are affixed on the stems of the jaw members 4 and may be of plastic material moulded upon the said members, and finger guards 9 are provided thereupon to prevent the fingers of any operator slipping onto the metal work.

The jaw members 4 are rockably connected by nutted screws 10 passing through orifices therein to a circular nut block 11, and spring washers 12 are inserted under the nuts on said screws 10 to allow of said jaw members 4 hinging and rocking about said nut block 11. A guide pin 13 passes through aligned slots in the said jaw members 4 and has milled nuts 14 upon its screwed ends with springs 15 thereunder, the tension of the springs being regulated by screwing the nuts 14 in or out. The curved jaw ends 5 are thus urged together, so as to engage firmly upon a spark plug top or the like, and to be kept closed 20 when not in use.

The adjustment rod 16 is screw threaded and of suitable length and passes through a threaded orifice in the nut block 11. It has a finger knob 17 of insulating material at one end, while the other end has a collar 18 of insulating material secured thereupon, said collar 18 having its outer end cut away to leave a buttress or shoulder 19 at one side, inwardly of which a spark gap 20 is formed between the rod end and a body against 30 which the shoulder 19 is abutted.

In use the improved device is clamped by its jaw ends 5, say to the terminal or top of a spark plug 7 as shown in dotted lines in Fig. 2, and the adjustment rod 16 which is adapted when not in use to be between the jaw members 4 (as shown in Fig. 1) is angularly adjusted on its pivots and the spark gap 20 formed by screwing the rod 16 by means of its finger knob 17 through its nut block 11 until the collar 18 is suitably positioned adjacent an earthing point, in this case the metal body 21 of the spark plug 7. The ignition system relative to the particular spark plug can then be readily tested by noting if the high tension current is reaching the said plug through the medium of the spark gap 20 and also revealing whether the said plug is functioning correctly.

It must be understood that the invention is not limited to the precise details of construction hereinbefore set forth but such changes and alterations as fairly fall within the spirit and scope of my invention may be made.

I claim:

1. Improvements in devices for testing spark plugs and ignition circuits consisting of a pair 55

of jaw members shaped at one end to engage with a spark plug terminal or the like and having handles of insulating material at the other end and being hingedly or pivotally connected together by a pivot member and having spring means to normally close said jaw members at the shaped end, and having an adjustment rod pivoted to said jaw members through said pivot member and arranged to be angularly adjustable in relation thereto and movable backwards and forwards about or through the pivot member, and carrying an outer contact end adapted to be adjusted with respect to an earthing point as the metal body of a spark plug or the like.

5 2. Improvements in devices for testing spark plugs and ignition circuits as defined in claim 1, in which the jaw members are rockably hinged together and have a stud or the like loosely passing transversely therethrough adjacent the 10 shaped jaw ends, and tension springs arranged on

15

15 20

said stud to bear upon and close the jaws inwardly, and nuts on said stud for regulating the tension of said springs.

3. Improvements in devices for testing spark plugs and ignition circuits as defined in claim 1, 5 in which the adjustment rod screws through a nut block disposed between the jaw members and to which said members are rockably hinged, a finger grip of insulating material mounted upon one end of said rod and an insulating collar arranged upon the other end of said rod with said rod end set in a slot or recessed portion of said collar to form a spark gap.

4. Improvements in devices for testing spark plugs and ignition circuits as defined in claim 1, 15 in which the handles of electrical insulating material have finger guards or the like formed thereupon to prevent the hand or hands from contacting the "live" metal parts.

JAMES TAWYER. 20
